UNITED STATES PATENT OFFICE.

LEWELLYN DANIEL DAVIS, OF SALT LAKE CITY, UTAH TERRITORY.

HOISTING-CAR.

SPECIFICATION forming part of Letters Patent No. 290,404, dated December 18, 1883.

Application filed October 8, 1883. (No model.)

To all whom it may concern:

Be it known that I, LEWELLYN DANIEL DAVIS, of Salt Lake City, in the county of Salt Lake and Territory of Utah, have invented 5 a new and useful Improvement in Hoisting-Cars, of which the following is a full, clear, and exact description, reference being had to the annexed drawings, forming part of this specification.

10 This invention relates to cars for hoisting ore out of an inclined shaft; and the invention consists of the construction hereinafter described and claimed.

In the drawings, Figure 1 is a side elevation 15 of the car and part of an inclined track, and Figs. 2 and 3 are respectively front and rear elevations of the same.

A indicates an iron box, mounted in any suitable manner upon a truck, B. To opposite sides of the box are pivoted two oscillatory draw-bars, C, having hooks D for attaching the chains E, which are connected to the cable F by a link, G.

H indicates two vertical guide-bars at the forward end of the car-box, within which the bars C are free to move. The truck also is provided with a draw-bar, H', which is connected to the link G of the cable by a chain, I.

The chains E and I are to be of such relative lengths that the draft will be thrown on the draw-bar H' and chain I on a horizontal track, and on the draw-bars C and chains E on an inclined track. By this construction the car is adapted to be drawn either along a horizontal track or up an inclined track with safety, and without the need of any special adjustment in passing from one such track to another.

The bars C are pivoted to the sides of the 40 box at points near the rear end of the latter, and preferably above the horizontal plane of its center, such points being beyond the center of gravity in an oblong box when the latter is inclined, as shown in the drawings.

45 Hoisting-cars have heretofore been provided with draw-bars pivoted to the upper and rear part of their sides, and in other cases a chain attached to the ordinary draw-bar of the car has been connected to another chain 50 attached to the upper part of the car by a removable hood, the two chains being connected

to a common cable. These constructions I do not claim, broadly.

In my invention the combination of the pivoted bars with the ordinary draw-bar, 55 and the intermediate chains connecting said bars to a common cable, and adapted to take the strain alternately as the track is inclined or horizontal, adapts the car for convenient use under a variety of circumstances without 60 the need of special adjustments, and this combination is believed to be new.

The box is provided with a sliding cover, J, which is held by cleats K, attached to the sides of the box, and is secured by a pin, L, 65 which engages with the cover, and a keeper, M, attached to the inner surface of its rear end.

The front end of the box is made in the form of a gate, N, hinged at its upper edge, and 70 secured by a button, O, which is rigidly attached to a shaft, P, arranged under the box, and adapted to be turned, to cause the button to engage the gate, by means of a hand-lever, Q, which is supported outside the rear 75 end of the box. This lever is passed through a squared hole in the rear end of shaft P, and has a hook, q, at its end, which is detachably inserted into a staple, R, in the rear end of the truck.

By removing the hook q from the staple R, the lever Q may be vibrated to oscillate the shaft P and button O. When the hook is in the staple, the shaft P is thereby locked to prevent the button O from accidentally turning and releasing the gate.

80 What I claim is—

1. The combination, with the draw-bar of a car-truck, of a pair of draw-bars pivoted to the sides of the car-box above the truck, said 90 draw-bars of the truck and box being connected to a single cable, substantially as shown and described.

2. The combination, with the draw-bar of a car-truck, of a draw bar or bars pivoted to 95 the sides of the car-box above, and to the rear of the center thereof, and the intermediate chains connecting said draw-bars independently to a common cable, substantially as shown and described, and for the purpose 100 specified.

3. The combination, with the box having a

hinged gate at one end, of the shaft arranged under the box, and having a button secured thereto for holding the gate, and the lever at the rear end of the box, connected to said shaft, and having a hook engaging with a staple for locking said shaft, substantially as specified.

4. The car-box having the hinged gate at one end and a sliding cover, substantially as shown and described.

LEWELLYN DANIEL DAVIS.
